W. N. Matthews Corporation, St. Louis, Mo., a
corporation of Missouri

Application March 24, 1939, Serial No. 263,857

4 Claims. (Cl. 200—114)

This invention relates to fuses, and with regard to certain more specific features, to closed type fuse switches.

This invention is an improvement upon the construction shown in my United States Patent 2,176,045, dated October 17, 1939 for Fuse.

Among the several objects of the invention may be noted the provision of a closed type of fuse switch of the class shown in said application in which a greater visible indication and electrical clearance is provided in its blown condition; and the provision of a switch of the class described in which a more complete enclosure is provided under unblown conditions. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a vertical section through the apparatus which is shown in closed, circuit-connecting position;

Fig. 2 is a horizontal section taken on line 2—2 of Fig. 1;

Fig. 3 is a horizontal section taken on line 3—3 of Fig. 1;

Fig. 4 is a bottom plan view of Fig. 1;

Fig. 5 is a view similar to Fig. 1 showing an intermediate blown condition, certain parts being shown in elevation;

Fig. 6 is a view similar to Fig. 1 showing a final blown condition, more parts being shown in elevation;

Fig. 7 is a view similar to Fig. 6 but in which the fuse switch is shown partly open and about to be closed;

Fig. 8 is an oblique section taken on line 8—8 of Fig. 7; and,

Fig. 9 is a fragmentary vertical section taken on line 9—9 of Fig. 6.

Similar reference characters indicate corresponding parts throughout the several views of the drawings.

Referring now more particularly to Fig. 1, there is shown at numeral 1 a box made of insulating material such as porcelain, supported by means of bolts 3, and having therein conducting line terminals 5. The line terminals in-

clude wire clamps 7 for respective line wires (not shown).

Associated with the upper line terminals 5 is a riveted U-shaped spring conducting member forming a knife type of contact 9. This contact 5 is of the variety in which the opposite holding faces of the spring members are substantially parallel.

To the lower line terminal 5 is riveted a different type of spring conducting member 10 (Fig. 10 9). This conducting member 10 is characterized by the fact that the spring arms are flared in a downward direction, and also outward. The arms are of springiness similar to that of the spring arms forming the knife contacts 9. 15

The box 1 has a large opening at the bottom, as indicated at 11. The unrestricted character of the opening simplifies the manufacture of the box, besides having other advantages which will be particularized. The box also has a front 20 opening 13 covered by a door 15 hinged on a pin 17. The door 15 is made of insulating material, such as "Bakelite," for example. Unlike the door of said application, the present door 15 is hinged at its upper end, the pin 17 being at the 25 upper portion of the box 1. The hooked-shaped portion 19 on the door which makes a hinge element is open as shown at 21 so that the door may be removed from the box after it has been pulled to an open position. A ring 23 is provided for 30 manipulation.

The door 15 has attached thereto, by means of screws 25, an upper, hollow, terminal-engaging element 27, made of conducting material, having flat sides 31 for engagement with the flat 35 sides of the U-shaped spring conducting contact 9 of upper line terminal 5.

The spring pressure between the spring arms of contact 9 and the terminal-engaging element 27 is substantial, so that a good contact is obtained under operating conditions without un- 40 due temperature rise in the switch.

The lower outer corners of the spring arms of contacts 9 are flared as shown at 30 to function as guides for the diagonal entrance of the upper terminal-engaging element 27. It will be noted in this connection that element 27 swings around the center of the pin 17 and therefore enters the contact 9 diagonally from below. It is for this reason that the flare 30 is angled. 45

The hollow portion of the upper terminal-engaging element 27 is open at the top and bottom, and at the top is threaded to receive an enclosing cap 35. The cap also functions as a clamp for the upper headed end 37 of a fuse link 39. 50 55

The fuse link 39 has a fusible portion 41 adapted to melt upon overload and to open the circuit. Its lower end is composed of flexible conducting wire 43.

5 The fuse link 39 passes through a fixed, inner, insulating tube 45 which is rigidly supported at its upper end by threading to the upper terminal-engaging element 27. The lower end of the tube 45 is open, as indicated at 47.

10 Slidably arranged on the insulating tube 45 is a second insulating tube or sleeve 51. The lower end of the sleeve 51 is provided with a relatively fixed collar 57 which may or may not be made of conducting material, although in the 15 present embodiment it is so shown. This collar is formed on one side with a smooth, rounded, anti-friction saddle 59 which permits sliding thereover of the fuse link wire 43 and directs it into tube 45.

20 The top of the collar 57 forms a seat for a flat bottom 2 which encloses the opening 11 (when the door 15 is closed). The bottom 2 is made of insulating material, such as fibre. It closes the bottom of the box at substantially all 25 points, with the exception of those at a slot 4 in the bottom 2 (see Fig. 4). The purpose of the slot 4 is to permit the upward direction of the flexible part 43 of the fuse link.

The bottom 2 also forms a seat for a spring 30 61. Above the spring 61 and slidably arranged upon the outside of the sleeve 51 is a lower terminal-engaging element 63, composed of conducting material. This element or contact 63 is attached by means of screws 6 to an insulating 35 guide plate 8. The screws 6 also extend into and slide in a slot 53 arranged in the tube 51, such that there is a limited relative motion between said outer tube 51 and the terminal-engaging element 63, to the extent indicated by 40 comparing Figs. 1 and 5.

45 The guide plate 8, which moves with the elements 63, slidably cooperates with the flat inner surface of the door 15. It has therein a slot 12 which surrounds a stationary pin 14 on the door 15 (Fig. 8). By this means the relative motion of the plate 8 (and consequently also of the lower terminal-engaging element 63) and the door 15 is allowed to the substantial extent indicated by comparing Figs. 1 and 6. Since the 50 plate 8 is flatwise against the door 15, it prevents rotary movement of the tube 51 on the tube 45.

The lower terminal-engaging element 63 is of 55 special form to mate with the lower line terminal 10, that is, the contact 63 flares downwardly primarily (Fig. 8). It also flares somewhat in the direction of the door.

Associated with the terminal-engaging element 63 is a clamp 68 threaded on a stud 66, by means of which the lower end 43 of the 60 fuse link 39 may be bound to the terminal-engaging element 63.

65 Operation of the device is as follows, assuming that the door 15 has been removed, and that a new fuse is required:

The cap 35 is removed and the old upper fuse portion element removed. Such lower fuse element 43 as may be held by the clamp nut 68 is also removed.

70 The new fuse is fed (flexible part 43 first) through the upper terminal-engaging element 27 and its head 37 is clamped in position by the cap 35. The lower end 43 of the fuse then extends from the lower end opening 47 of the fixed tube 45, and from the lower open end 67

of the movable ring 57. It is threaded around the smooth saddle 59 and then turned upwardly through the slot 4. Its end is then fastened by means of the clamp 68. Before fastening is made, as much as possible of the fuse end 43 is drawn from the tube 45, thus tensioning the fuse 5 39. Tension may or may not be placed in the spring 61 at this time. In any event the slidable tube 51 (fastened to the collar 57) is pushed up as high as it will go on the fixed tube 45. 10

Next, the door 15, while open, has its hook 19 applied under the pin 14 (Fig. 7) and is then rotated down into closed position (Fig. 1). This causes the upper flat-faced terminal-engaging element 27 to be frictionally engaged by the flat-faced spring arms 9.

15 The lower terminal-engaging element 63 is at this time at such an elevation on door 15 that it is springingly engaged by the spring arms 10 of the lower line terminal. The reaction between the outwardly and downwardly flowing line arms 10 and the upwardly and inwardly tapered terminal-engaging element 63 causes the latter to be pressed downwardly against the spring 61 to compress the latter. This pushes 20 down saddle 59 and places tension in the fuse link. It should be understood at this point that the bottom 2 moves with the collar 57 and is free of the plate 8, although slidable thereon. The element 63 and the plate 8 move down twice 25 the distance that the fuse link 39, 43 allows collar 57 and tube 51 to move down.

30 At this time, the reaction between the terminal-engaging element 63 and the clip 10 causes a satisfactory low-resistance surface contact 35 which has the effect of preventing the building up of switch temperatures.

35 The surfaces between the terminal-engaging element 63 and clip 10 are so arranged that the component of force exerted downwardly is of a 40 degree properly to tension the fuse link. The direction of this force for contact reaction is such that the door 15 is not forced open against the holding action of clip 9.

45 Upon overload, the fusible fuse portion 41 melts or blows. This releases the saddle 59, and the spring 61, having theretofore been under compression, forces the saddle down. This must be, because the terminal-engaging element 63 is held down by clip 10. The saddle 59 being part 50 of the collar 57 draws down the attached outer tube 51, until the upper end of the slot 53 (in tube 51) strikes the end of the upper one of the screws 6 (Fig. 5).

55 This provides an impact or blow to the lower terminal-engaging element 63 to drive it away from engagement with the line terminal 10. It is to be understood, however, that even without this blow the spring squeezing action of the lower downwardly flared line terminal 10 would normally squeeze the terminal-engaging element 63 out and down so that the latter would be forced out of contact. It will be understood that at this time there may also be an explosive action through the tube 45 due to blowing of the fuse 60 link, depending upon the degree of overload.

65 As indicated in Fig. 6, the assembly of tube 51, element 63, collar 59, bottom 2, spring 61 and plate 8 slides down until the pin 14 on the door 15 is reached by the end of the slot 12. 70 Support is then by the pin 14, the short telescoped relationship between tubes 45 and 51 at T functioning to steady the assembly. At this time, the lower portion of the fuse link 43 hangs downwardly. It is at this time electrically dead. 75

since the terminal-engaging element 63 is separated from its line terminal 10.

Among the advantages of the invention are those specified in my said prior application, together with the following:

By eliminating the hinge at the bottom of the door and placing it at the top of the door, the bottom of the box is left entirely clear for clearing parts to drop. Thus it is practicable to employ an enclosing bottom which may drop away as described, without increasing the size of box 1. Another feature is that more visibility is obtained by dropping down more parts for a greater distance. More parts can be dropped away because there is no interference at the bottom opening of the box when the hinge is arranged at the top.

Also, better visibility is obtained to indicate blown conditions, and better electrical clearance is obtained. At the same time, the circuit opening parts are held captive.

In view of the above, it will be seen that the several objects of the invention are achieved and other advantageous results attained.

As many changes could be made in the above construction without departing from the scope of the invention, it is intended that all matter contained in the above description or shown in the accompanying drawings shall be interpreted as illustrative and not in a limiting sense.

I claim:

1. A fuse switch comprising a box, line terminals in the box, said box having an open front and an open bottom, a door hinged near the upper end of said opening, a fuse supported on the door, terminal-engaging elements on the fuse engageable with the line terminals when the door is closed, one of said terminal-engaging elements being releasable from one of the line terminals when the fuse blows, means movably supporting said releasable disengaging element directed to direct the element out of said bottom opening of the box when the fuse blows, and means associated with the disengageable element to close the bottom of the box during engagement but to open said bottom upon disengagement.

2. A fuse switch comprising a box having a side opening and a bottom opening, upper and lower line terminals in the box, a door for the box hinged near the top of said side opening, a fuse carried by the door having an upper fixed

terminal-engaging element for fixed engagement with the upper line terminal, a lower terminal-engaging element movable on the door, a fuse link joining said engaging elements and adapted when unseparated to hold the lower engaging element in position for engagement with the lower line terminal upon closure of the door, said movable engaging element upon blowing of the fuse being adapted to move away from the lower line terminal and out of the bottom of the box.

3. A fuse switch comprising a box having a side opening and a bottom opening, upper and lower line terminals in the box, a door for the box hinged near the top of said side opening, a fuse carried by the door having an upper fixed terminal-engaging element for fixed engagement with the upper line terminal, a lower terminal-engaging element movable on the door, a fuse link joining said engaging elements and adapted when unseparated to hold the lower engaging element in position for engagement with the lower line terminal upon closure of the door, said movable engaging element upon blowing of the fuse being adapted to move away from the lower line terminal and out of the bottom of the box, and a bottom carried with said movable engaging element adapted to close the bottom opening when the movable engaging element is engaged and vice versa.

4. A fuse switch comprising a box having a side opening and a bottom opening, line terminals in the box, a door for the box hinged near the top of said side opening, a fuse carried by the door having an upper fixed terminal-engaging element for engagement with the upper line terminal in the box, a lower terminal-engaging element movable with respect to the door, a fuse link joining said engaging elements and adapted when unblown to hold the lower engaging element for engagement upon closure of the door, said movable engaging element upon separation of the fuse link being adapted to move away from the lower line terminal and out of the opening at the bottom of the box, a bottom for the box carried by said movable engaging element and adapted to be positioned to close said bottom opening when the movable engaging element is engaged and to move away from said opening upon disengagement of the movable engaging element.

THEODORE BIRKENMAIER.
